SMOKING TOBACCO PRODUCTS

Oliver S. North, 2119 H St. NW, Washington 7, D.C.

No Drawing. Filed June 12, 1957, Ser. No. 665,120

3 Claims. (Cl. 131—17)

This invention relates to smoking tobaccos for cigarettes, pipes and cigars, and more particularly to a tobacco having associated therewith a quantity of a certain additive, which mixture when smoked will produce a filtered smoke.

A number of compositions for and methods of filtering nicotine, dust and impurities from tobacco smoke before it is drawn into the smoker's mouth are known. Many of these are expensive and inconvenient to manufacture and/or use, and it is desirable to provide a product having self-contained and inexpensive, yet relatively effective, means for accomplishing filtration of the smoke.

A principal object of this invention is to provide a tobacco composition which when smoked will have the smoke filtered of a large portion of its content of nicotine and tars, dust and impurities.

Another object is to provide tobacco compositions and products that can be manufactured at a cost lower than or closely comparable to that of like standard articles of commerce.

Another object is to provide smoker's products having the size, shape and general appearance of standard commercial products.

Broadly speaking, the objects of this invention are accomplished by disseminating quantities of unexpanded vermiculite in the tobacco.

I have discovered that a tobacco product in which is incorporated a quantity of unexpanded vermiculite particles will swell when it is smoked, due to the fact that the burning tobacco particles produce sufficient heat to bring about exfoliation and marked expansion of the intimately associated crude vermiculite particles.

To accomplish at least partial filtration of smoke as the burning progresses, only a relatively very small amount of unexpanded vermiculite is used. When a cigarette so constituted is smoked there is sufficient expansion of vermiculite particles located at the point of spark to provide a plurality of thin platelets through which the smoke will be drawn to accomplish desirable filtration and prevent nicotine and impurities from being drawn into or through the remaining body of the cigarette, yet at the same time there is insufficient volume increase to split the wrapper paper or otherwise to disrupt the cigarette. As burning of the cigarette progresses, successive portions of vermiculite thus expanded are discarded along with the tobacco ash. This type of filtration is preferable to that accomplished by filter sections, or "filter tips," because a filter section, of whatever composition or type, tends to become progressively more clogged with accumulating tars, nicotine, etc., as smoking proceeds, thus losing some of its effectiveness. Furthermore, it is generally somewhat more economical to manufacture a cigarette composed wholly of a mechanical mixture of materials than one requiring provision of a special section or tip which is separate from the main body of the cigarette.

I am aware that there is described in U.S. Patent No. 2,786,471, issued to Kenneth Wayne Graybeal, a cigarette filter section composed of expanded vermiculite. How-

ever, expanded vermiculite is a chemically and physically different material than is unexpanded vermiculite, and it is more expensive, having undergone an additional heat-treating step. Further, the proposal has not been made to mix the vermiculite intimately with the tobacco throughout the body of the cigarette.

Vermiculite is a micaceous, hydrated magnesium-aluminum silicate mineral which is well known in industry, particularly in the construction, chemical and agricultural fields. While vermiculite is of fairly widespread mineralogical occurrence, the bulk of the commercial material now comes from the States of Montana and South Carolina, in the United States, and the Transvaal, Union of South Africa. As prepared for the market, ores containing crude vermiculite are mined and then beneficiated, or purified, by various methods of concentration and sizing, so that the final product consists almost entirely of unexpanded vermiculite flakes of uniform thickness and lateral dimensions. Different grades, or sizes, of material are commercially available. Expansion, or exfoliation, of vermiculite can be accomplished at relatively very low temperatures, for example by a match flame, as contrasted with most other expandable inorganic materials which require much higher heats. Expansion is caused by separation and warping of the individual laminae, so that the final particle consists of a succession of extremely thin plates stacked one atop another and separated from each other by more or less flat air spaces, and possessing a very large surface area.

SOME AVERAGE PHYSICAL AND CHEMICAL PROPERTIES OF VERMICULITE

[In part from Publication G-81, Zonolite Company, entitled "Chemical and Physical Properties of Zonolite Brand Vermiculite"]

Property	I	II	III
	Unexpanded	Commercially expanded	Expanded at thermal conditions of burning tobacco
Bulk density, lbs./cu. ft.	60	6	10
H ₂ O content, percent	6-12	0.5-1.0	1-2
Ion exchange, milliequivalents per 100 g.	25-100	3-15	20-60
Surface area (H ₂ O method), sq. meters per gram	250	10	100

It may be here pointed out that a ton of unexpanded vermiculite, which can be bought for a few dollars, will make many thousands of any of the products described, and therefore this material is most economical to use for these purposes. The cost per unit of the products described very closely approximates the cost of similar products made without vermiculite.

Vermiculite is an inorganic material, and during the expansion process contemplated in the present invention is free of violent effects, disagreeable odors or tastes, or any other form of objectionable manifestation.

This expansion, which commonly results in more than a tenfold increase in bulk volume, is due to the mechanical separation of the laminae when the contained water is converted into steam.

In manufacturing the products of this invention I intimately mix together quantities of unexpanded vermiculite particles and tobacco. I prefer to use commercially-available cured particulate smoking tobacco or, in the case of cigars, commercially-available cigar tobacco leaf, and commercially-available unexpanded vermiculite. The tobacco used may contain additives, such as for binding or flavoring or otherwise improving the qualities of the finished product, or such additives may be added during or after mixing of the tobacco and unexpanded vermiculite.

I shall describe in the following paragraphs the generally preferred compositions and methods of formulation of the various products at issue here. It will be understood that in all instances the proportions cited are merely examples, and that in each type of product the proportions used may vary over a greater or lesser range, and that I do not wish to limit the scope of this invention as regards the proportions of the materials used.

Filter cigarettes and cigarette tobacco compositions

A large proportion, for example 95 to 99 percent, by weight, of the desired cigarette tobacco is intimately mixed with a small amount, for example 1 to 5 percent, by weight, of unexpanded vermiculite. Generally, it will be preferable to use one of the intermediate partial size grades of vermiculite, for example the currently available commercial grade of which, by weight, about 95 percent will pass a 28-mesh Tyler screen and 80 to 85 percent of which will be retained on a 65-mesh Tyler screen. The vermiculite-tobacco mixture, with or without additives for flavoring or cooling purposes or the like, is formed into cigarettes by any of the known methods, or it may be packed in suitable sacks, boxes, cans or the like for subsequent use in hand-rolled cigarettes.

I have found that despite the differences in specific gravity and physical form of the granular vermiculite and the shredded tobacco, the materials will be so effectively held in a firmly wrapped cigarette that vermiculite particles will not readily become dislodged from the butt of the cigarette and drawn into the smoker's mouth. I believe this to be due partly to mechanical adherence of tobacco to vermiculite and partly to the wrapping around of vermiculite particles by tobacco shreds during the mixing of the two materials.

Pipe tobacco compositions

The pipe tobacco compositions here considered are made by intimately mixing the desired pipe tobacco with unexpanded vermiculite. Up to about 35 percent, by

weight, of unexpanded vermiculite may be used. Because of the usual relative coarseness of pipe tobaccos, it will generally be found preferable to use a coarser grade of vermiculite than is used in cigarette tobaccos. For example, a commercial grade having a substantial proportion of the particles as large as 8-mesh may be used.

The particulate vermiculite-tobacco mixture is packed in suitable cans, boxes, "tins," or other type of container for subsequent use in pipes.

Cigar compositions

In the manufacture of cigars in accordance with this invention, unexpanded vermiculite flakes may be deposited either on several or all of the leaves, prior to rolling, or on the exterior leaf or leaves only, or disposed at the core of the cigar.

I claim:

1. A smoking mixture consisting essentially of tobacco and from 1% up to 35% by weight of unexpanded vermiculite intimately admixed with the tobacco and uniformly distributed throughout the mixture.
2. A smoking mixture consisting essentially of between 95% and 99% by weight of tobacco and between 1% and 5% by weight of unexpanded vermiculite intimately admixed with the tobacco and uniformly distributed throughout the mixture.
3. A cigarette consisting of a wrapper enveloping the mixture of claim 2.
